LOCKING DEVICE FOR LOOSE LEAF BINDERS
AND THE LIKE

William J. Weatherly, Tampa, Fla.

Application June 23, 1937, Serial No. 149,857

1 Claim. (Cl. 129—13)

This invention relates to a locking device for loose leaf binders and the like.

One object of the invention is to provide a locking device which is simple and economical to construct, easy to operate and which provides a positive lock against undesired expansion of the binder but which permits ready compression of the binder and its contents.

The lock is particularly applicable to catalog binders used by salesmen for wholesale and jobbing houses dealing in a large range of merchandise. Such salesmen must ordinarily carry extremely bulky catalogs made up in loose leaf form.

Other objects and features of the invention will be understood from the accompanying drawing and the following description and claim:

Fig. 1 is a perspective view of a complete loose leaf catalog binder with the contents removed and showing the invention applied thereto. Fig. 2 is a sectional view taken on the line 2—2 of Fig. 1. Fig. 3 is a plan view of the lock per se with parts shown in section. Fig. 4 is a sectional view on the line 4—4 of Fig. 3.

In the form of the invention shown in the drawing by way of illustration, there is provided a catalog binder including a pair of metallic backing members 10 and 11 substantially L-shaped in cross section. Each of said members has hinged thereto a metallic strip 12 to which there is secured a sheet 13 of leather or other suitable flexible material. Handles 14 are attached to the sheets 13 for carrying the binder and contents. The member 11 is provided with an upwardly and inwardly turned flange 15 along each edge which flanges embrace the edges of the member 10 and provide a guideway for sliding or telescoping the backing members with respect to each other. A pair of binder rods 16 is secured by any suitable means to the upstanding portion of the member 10 and similar rods 17 are secured to the upstanding portion of the member 11. These rods are spaced to engage mating holes provided in the catalog sheets to be carried in the binder.

Mounted adjacent the inner edge of the member 10 there is provided a keeper 18 preferably formed of sheet metal and open at both ends. Said keeper is located below the level of the rods 16 and 17 so as not to interfere with the edges of the catalog sheets. A rod 19 is secured to the upturned portion of the member 11 and passes through suitable openings in the side walls 20 of said keeper. A lever 21, preferably channel-shaped in cross section, extends within

the keeper 18 and outwardly to a position adjacent the edges of the members 10 and 11. Within the keeper 18, said lever is provided with a suitable opening through which the rod 19 may pass and is provided with an enlarged inner portion 22 engaging one of the side walls 20. A leaf spring 23 secured to the back of the lever 21 engages the opposite side wall 20 on the opposite side of the rod 19. This spring normally urges the lever in a counterclockwise direction about the point of contact of the part 22 and wall 20. The lever is, therefore, in effect, pivotally mounted upon the backing member 10 at this point. The opening in the lever 21 through which the rod 19 passes is made to fit said rod 19 relatively closely so that when the lever 21 is angularly disposed to the rod 19 the edges of said opening grip the rod and prevent sliding movement of the rod through the opening.

In the use of the apparatus, when loose leaf sheets have been placed on the rods 16 and 17, the two halves of the binder may be pressed together to compress the contents and to hold the same firmly in place. In this compression, the frictional engagement of the rod 19 with the lever 21, tends to pivot the lever in the direction of the arrow 24 in Fig. 3, thus compressing spring 23 and placing the lever 21 substantially at a right angle to the rod 19. In this position, the rod 19 may freely slip through the lever 21 and the binder may be compressed as much as desired. Any tendency for the rod 19 to be moved in the opposite direction through the lever 21 is resisted by the action of the spring 23 which tends to move the lever 21 in the direction of the arrow 25. In any such movement, the frictional engagement of the lever 21 and rod 19 tends to cause said lever to assume an even more angular position and thus strongly resist any undesired expansion of the binder and its contents.

When it is desired to expand the binder, the lever 21 is manually pressed in the direction of the arrow 24 and is held at a right angle to the rod 19 which may then be freely withdrawn.

The foregoing specification describes a preferred form of the invention, the details of which may be varied within wide limits without departing from the scope thereof as defined by the appended claim.

The invention claimed is:

In a loose leaf binder or the like having a pair of relatively movable backing members, a rod secured to one of said members, and a keeper having opposed side walls secured to the other of said members, the combination of a lever having

one end positioned between said side walls and the opposite end extending outside of said keeper to a position accessible for manual manipulation, said lever having a close fitting opening 5 through which said rod may pass and having a rounded portion rockingly engaging one of said walls at one side of said rod, and a spring secured to said lever and engaging the other of said side walls and on the opposite side of said 10 rod, said lever and spring being freely insert-

able and removable between the walls of said keeper as a unit when said rod has been withdrawn, and said spring tending to force said lever into an angular position in which the edges of said opening clamp said rod to prevent relative movement thereof, whereby said lever must be manually moved to a different position to permit such relative movement. 5
